UNITED STATES PATENT OFFICE.

WILLIAM H. BRIDGES, OF GRAND RAPIDS, MICHIGAN, ASSIGNOR TO BENJAMIN FELD,
OF FULTON COUNTY, GEORGIA.

TOILET-BRUSH.

1,272,908.

Specification of Letters Patent. Patented July 16, 1918.

Application filed August 11, 1915, Serial No. 45,044. Renewed May 13, 1918. Serial No. 234,341.

To all whom it may concern:

Be it known that I, WILLIAM H. BRIDGES, a citizen of the United States, residing at Grand Rapids, in the county of Kent and 5 State of Michigan, have invented certain new and useful Improvements in Toilet-Brushes, of which the following is a specification.

My invention relates to improvements in 10 folding toilet brushes, and its objects are: first, to provide an improved means for folding the bristles down within the brush frame, and extending them out at right angles with the frame; second, to provide a 15 means whereby the bristles may be made to occupy the least possible space in the frame of the brush, when folded, and will extend to the full length of the bristles outside the surface of the brush frame when extended; 20 third, to provide a means whereby there will be actually no unsightly open space between the first row of bristles and the adjacent end of the handle or extensible part of the brush frame when the bristles are extended, and 25 by which a sufficient space will be created, upon folding the bristles into the frame of the brush, so that there will be no possibility of the end of the handle coming in contact with the ends of the bristles as the 30 handle is being forced toward the frame of the brush for extending the bristles; fourth, to provide a means whereby the movement of the bristle holders from extended to folded positions, and vice versa, will be absolutely smooth, positive and free in action, and, fifth, to provide a means whereby the 35 bristles will be held firmly in position when extended ready for use for brushing purposes.

40 I attain these objects by the construction and assembling of parts shown in the accompanying drawing in which Figure 1 is a face plan of a brush frame and the bristle holders with the bristles removed, the brush 45 being of the class known as "military brushes"; Fig. 2 is a longitudinal section of a brush frame and handle showing the permanent actuating bar, and the actuating slide in position; Fig. 3 is a longitudinal section of the brush frame showing the normal 50 positions of the two actuating bars when the bristles are extended; Fig. 4 is a longitudinal section of one end of the brush frame showing the actuating bars in normal position and the bristle bars and bristles in ex-

tended position; Fig. 5 is a longitudinal section of the brush frame practically on the line x , x of Fig. 1 showing the pivotal bearings of the bristle holders and the bristles in folded position; Fig. 6 is a plan, and Fig. 60 7 is an elevation of the adjustable actuating bar; Fig. 8 is an edge view of the permanent actuating bar, and Fig. 9 is a side elevation of the bristle bar and its pivot frame.

Similar reference characters represent 65 similar parts throughout the several views.

In the construction of this brush I make a sheet metal frame 1 having the sides at right angles with the back, and each side having an inwardly extending edge h of a 70 proper width to form a recess at each side of the frame of a proper depth to cover and secure the upper edges of the actuating slide 5 and the movable actuating bar 7, as indicated in Fig. 1. 6 represents a permanently 75 located actuating bar that is located in the lower half of the recess on each side of the brush frame, and is made of the same thickness as the width of the edge h of the side of the frame, or, in other words, as thick as the 80 combined thickness of the actuating slide 5 and the actuating bar 7 so that when these elements are placed in the recesses the inner surfaces of the bars 6 and 7 will be in the same plane.

85 The actuating slide 5 is securely connected, at one end, with the side of the handle guard 4, on handle brushes, or the side of the extensible frame 2 on military brushes, one of said slides being provided for each 90 side of the brush. These slides are made to exactly fit and slide freely between the lower surfaces of the inturned edges h of the frame 1, and the upper edge of the permanent adjusting bar 6, and each slide is 95 provided with a slot near each end, each slot having a long part a of uniform width at the forward ends, and an inclined part b , c , at the back ends. These slides lie directly against the side walls of the brush frame 100 and in position so the pins d , d that extend outward from the surfaces of the actuating bars 7, 7 will pass through the slots hereinbefore described. The long portion a of the slots is designed to allow the slide to be 105 drawn backward for some distance before the bristle bars 9 are affected by the actuating bars 7, 7. This is for the purpose of forming a space between the guard 4 of the handle and the first bristle bar 9 as long as 110

the full length of the bristles before the bristles are turned down to folded position, as indicated in Fig. 5. The pins *d*, *d* are actuated by passing the inclines *b* and *c* to move the actuating bars *7*, *7* so they will cause the bristle bars *9* to be thrown from the position indicated in Figs. 1 and 4 to that shown in Fig. 5. The movement of the actuating slides backward when the pins *d*, *d* are passing over the inclines *c* and *b*, and before the handle guard 4 has approached close enough to touch the ends of the bristles on the first bristle bar, will carry the bristle holders and the bristles back to position at right angles with the brush frame. The balance of the distance traveled by the slides before the pins *d*, *d* are engaged by the slide at the end of the portion *a* of the slot allows the slide to move far enough to close up the space between the handle guard 4 and the first row of bristles.

In explaining the manner in which the bristle bars *9* are actuated we will presume that the normal positions of the several parts of the brush are represented in Figs. 1, 2, 3 and 4. In these figures the pins *d*, *d* are located at the, relatively, right hand end of the slots *a* and the pivot holes *e* are located relatively to the left of the corresponding holes, *f*, in the permanent actuating bars *6* so that when properly assembled the pintles *i* at the upper ends of the bristle bar frames 10 will be passed through the respective holes *e* in the bar *7* to the left of the corresponding holes *f* in the permanent bars *6*. The pintles *j* at the lower ends of the frames 10 are pivotally anchored in the bars *6*, as at *f*, so that when the handle 3, or the part 2 of a military brush, is drawn back and the slides 5 are drawn out of the frame far enough to cause the pins *d*, *d* to be engaged by the plates or slides 5 at the end *c* of the slots *a*, *b*, *c* and draw the bars *7* endwise, the upper ends of the bristle bar frames 10, will be drawn forward by the bars *7* and the bristles will be caused to assume the positions indicated in Fig. 5, when all of the bristle ends will be below the edges *h*, *h* of the brush frame 1. From this position the reverse movement of the slides 5, 5 will carry the bristle bars and bristles back to the position shown in Fig. 4.

I prefer that the bars *6*, *6* be placed far enough away from the back of the brush frame to form a crease or slot for the free passage of the back 8 of the handle or sliding part of the brush. It will be readily understood that this, together with the confinement of the slides 5, 5 between the overhanging edges *h*, *h* of the frame, and the upper edges of the bars *6*, *6* will form guides and guideways that will cause the handle or sliding part of the brush to move in the frame in a direct line without danger of cramping in the least degree.

It is evident that when the bristle holders and bristles are in the position indicated in Fig. 4, and the brush is in use, either for brushing the hair or for brushing the clothes, it will be necessary to provide some means by which they will be held securely in place. For this purpose any of the ordinary forms of catches may be utilized; as indicated by the latch 13, pivotally connected at *m* and actuated by the thumb piece 12 and the spring *n*, the point *k* being made to pass through a slot in the back plate 8 and to engage a slot *l* in the frame back 1 when the slides and bristle bars are in the positions indicated in Figs. 1 and 4.

It is necessary to make the sliding actuating bars *7*, *7* somewhat narrower than the spaces between the edges *h*, *h* of the frame and the upper edges of the permanent bars *6*, *6* so they may be readily adjusted to the edgewise movement caused by the pins *d*, *d* operating in the inclines *b*—*c*, and to carry the bars *7*, *7* low enough, or far enough back in the frames to cause the bristles 11 to lie entirely within the walls of the frame.

o, *o* represent holes in the edges of the bristle bars for the reception and retention of the bristles.

What I claim as new, and desire to secure by Letters Patent of the United States, is:

1. A toilet brush consisting of a frame having a recess formed in each side, an actuating bar permanently secured in the lower half of each of said recesses and having a series of holes formed therein, slides located in the recesses between the permanent bars and edges of the sides of the frame and provided with suitable slots, means for reciprocating said slides, sliding bars mounted at the sides of the slides and provided with pins that extend into the slots in the slides, and bristle bars having pins projecting longitudinally from each end into the holes in the permanent bars and having means engaging the sliding bars to operate the bristle bars to extend or fold the bristles.

2. In toilet brush construction, a frame having a recess formed in each side, an actuating bar permanently secured in the back halves of the recesses, actuating bars slidably secured in the forward halves of the recesses, slides connected together at one end and arranged between the sliding actuating bars and the sides of the frame, said bars being provided with slots straight at one end and having oppositely directed inclined portions at the other ends, pins on the sliding actuating bars extending into said slots, the permanent actuating bars and the sliding actuating bars having holes through them for mounting bristle bars, bristle bars pivotally mounted in said actuating bars, and means for moving the slides endwise for opening and closing the bristle bars, substantially as shown and described.

3. In toilet brush construction, a sheet metal frame, an actuating bar permanently secured to the inner surface of each side of the frame, a sliding bar in each side of the frame, an actuating slide adjacent to each sliding bar, bristle bars pivotally mounted between the respective pairs of sliding and actuating bars, means connected with the slides to fold or extend the bristle bars, and 10 means for locking the slides in place.

4. In a toilet brush, a sheet metal frame having recesses formed in the sides, actuating bars secured to the sides in said recesses forming a slot at each side between 15 said bars and the back of the frame, a handle having a slide at the back to work in the slots formed by the actuating bars, a slide at each side of the handle extending into the recesses in the frame and having properly 20 formed slots therein, a sliding actuating bar in each side of the frame, pins on said bars to engage the slots in the slides, bristle bars pivotally mounted in the actuating bars, means for operating the slides to actuate the 25 sliding actuating bars to fold or extend the bristles of the brush, and means for locking the slides in fixed position when the bristles are extended.

5. In combination with the channeled 30 sheet metal frame of a toilet brush, actuating bars permanently secured in the sides of the frame forming slots between them and the back of the frame, a handle having a sheet metal back extending longitudinally therefrom to slide in said slots, slides connected 35 with the sides of the handle and extending longitudinally of the sides of the frame, sliding actuating bars so connected with the slides as to be given a longitudinal, and slightly 40 lateral movement when the slides are moved lengthwise of the frame, bristle bars so pivotally connected with the actuating bars that the longitudinal movement of the slides will extend or fold the bristles, as desired.

45 6. In combination with a channeled brush frame, relatively stationary bars arranged within the frame, adjacent opposite sides

thereof, a sliding actuating bar arranged adjacent each of said stationary bars, each of said sets of bars being provided with 50 transverse passages, the passages in the sliding bars being normally out of alignment with those in the stationary bars, bristle supporting frames having at both ends projecting pins that extend into the passages 55 in the sliding and stationary bars, slides supported by the frame and having slots extending parallel with the length of the slides and frame for a suitable distance and then inclined from parallel position, and projections on the sliding actuating bars extending into the said slots in the slides, for the purpose described.

7. In toilet brush construction, a channeled frame having inwardly opening recesses at the sides, actuating bars permanently secured in the back half of said recesses and having a row of holes through them, sliding actuating bars mounted in 65 said recesses edgewise with the permanent 70 bars and having holes therethrough normally alternating with the holes in the permanent bars, said sliding bars narrower than the remaining space in the recesses, a handle, slides extending from the end of 75 the handle into the space back of the sliding bars, said slides having slots through them horizontal for a distance, from one end, thence inclining upward and backward and thence downward and backward from the 80 horizontal forming two angles at the other end, pins extending from the sides of the sliding actuating bars into said slots and so arranged that the longitudinal movement of the slides will move the actuating bars longitudinally and laterally, and bristle bars, pins 85 at the ends of the bristle bars arranged to engage the alternating holes in the actuating bars so the longitudinal movement of the sliding bars will actuate the bristle bars 90 to extend and fold the bristles.

Signed at Grand Rapids, Michigan, August 4, 1915.
